(57) **CLAIM**

The ornamental design for a water bottle, as shown and described.

DESCRIPTION

FIG. 1 is a perspective view of a water bottle showing my new design;

FIG. 2 is a front elevation view thereof; the side elevation views being identical;

FIG. 3 is a top view thereof;

FIG. 4 is the first image in a first sequence for the water bottle with an animated interface;

FIG. 5 is the second image thereof;

FIG. 6 is the third image thereof;

FIG. 7 is the fourth image thereof;

FIG. 8 is the fifth image thereof;

FIG. 9 is the sixth image thereof;

FIG. 10 is the first image in a second sequence for the water bottle with animated interface; and,

FIG. 11 is the second image thereof.

The appearance of the animated graphical user interface sequentially transitions between the images shown in FIGS. 4-11. The process or period in which one image transitions to another forms no part of the claimed design.

The broken lines showing portions of the water bottle form no part of the claimed design. The dash lines on the water bottle represent an unclaimed boundary line and forms no part of the claimed design.
